INVENTOR
John Ballou

UNITED STATES PATENT OFFICE.

JOHN BALLOU, OF SOMERVILLE, MASSACHUSETTS.

STOVE OR RANGE.

SPECIFICATION forming part of Letters Patent No. 524,736, dated February 26, 1895.

Application filed July 25, 1894. Serial No. 518,564. (No model.)

To all whom it may concern:

Be it known that I, JOHN BALLOU, of Somerville, county of Middlesex, and State of Massachusetts, have invented certain new and 5 useful Improvements in Cooking Stoves or Ranges, of which the following is a specification, reference being made to the accompanying drawings, in which similar letters refer to similar parts, and in which—

10 Figure 1 shows an isometrical view of a stove or range containing my invention, portions of the stove being broken away to display the invention more clearly as to the interior arrangement. Fig. 2 shows an isometrical view substantially like Fig. 1 but giving an exclusively exterior view. Fig. 3 is a vertical section of a range on line XX, Figs. 1 and 2.

15 This invention relates to cooking stoves or ranges and especially that class known as portable ranges, and the invention consists in the combination and arrangement of flues and dampers in connection with the fire chamber and ash or sifting chamber of a range, and 25 the object of which is to provide means by which communication of the most positively direct character is effected between the fire chamber, or ash or sifting chamber, and the chimney, for purposes hereinafter set forth 30 more specifically.

35 A, represents a flue extending horizontally the entire length at the back and at the outside of the range, the top B, of the range forming also the top of the flue, all of the products of combustion passing directly from the flue A to the chimney.

40 At the end of the flue A or that portion adjacent to the fire chamber C, an opening D is provided, communicating with the upper 45 part of the fire chamber, and to which opening a damper E is fitted. At the same end of, and from the flue A extending vertically, is a branch flue F communicating with the sifting (or ash) chamber G by means of the 50 opening H, the vertical flue F being provided with a damper I. Immediately over the vertical flue F, and in the top of the flue A, is provided an aperture J adapted to receive a collar, or smoke pipe to convey the products 55 of combustion to the chimney.

From the foregoing description it will be seen that the flue A—which as is usually constructed in stoves of this character terminates at or near the center of the back of the stove,—is in this invention extended to the extreme 55 fire chamber end of the stove and communicating with the fire chamber, permits the products of combustion to pass to the chimney by the most direct means possible while the vertical flue F communicating with the 60 sifting (or ash) chamber, furnishes similar direct passage from that apartment to the chimney.

The advantage of the form of construction presented in this invention, consists in the 65 fact that by means of this direct passage from the fire chamber to the chimney, a fire may be maintained in the fire chamber and the products of combustion—naturally taking the most direct or shortest course to the 70 chimney—will pass through the opening D, thence to the chimney, and thus, a fire of considerable volume may be maintained, and over which a considerable amount of light cooking may be accomplished,—not of course 75 using the oven—while the major portion of the stove will be entirely cold, features that are very desirable and duly appreciated by the housewife during a large portion of the heated term of the summer months. By this 80 direct course to the chimney of the products of combustion, and especially in connection with a smoke pipe fitted to the aperture J or J', not only are the advantages above set forth attained, but by means of this short 85 course to the chimney the draft of the stove is greatly increased and the kindling or starting of the fire facilitated.

85 The damper E may be adjusted by means of the handle K, to close the opening D at 90 the will of the operator, following which, the products of combustion will pass around or over the oven, following the course common to this class of stoves that are provided with the usual flues and dampers.

95 The advantages of the vertical flue F, are that by means of the communication with the sifting (or ash) chamber G, when the fire grate is shaken or dumped, the dust arising from the ashes, are by the draft of the 100

chimney drawn through the opening H and up the chimney, thus preventing its escape through the various crevices about the door of the stove, or to be carried up and deposited 5 within the flues surrounding the oven.

The damper I by means of the handle L, may be adjusted to close or open the flue F as may be desired. The damper I as shown in the drawings is arranged to lie upon the 10 bottom of the flue A, and is drawn in or out in a direction corresponding to the length of the flue A, while the damper E is arranged to swing from a vertical position when closed, to a position approaching the horizontal when 15 open.

The objects of the dampers I and E being simply to permit the apertures H and D respectively to be opened or closed as may be desired, they may either, or both of them 20 be varied in the arrangement or construction without departing from the spirit of the invention.

A series of apertures J, M, N, one at each 25 end and one in the center at the top of the flue A, to either of which a collar or smoke pipe may be fitted, while corresponding apertures J', M', N', of a similar character and purpose at the back of the flue A admit of the smoke pipe being placed at either end or 30 the center of the stove as may be most convenient, but for the purposes of this inven-

tion the aperture J, or J', is deemed most desirable.

The drawing Fig. 3 shows the ash chamber O as an apartment distinct from the sifting 35 chamber G. Many ranges have only one apartment here, and for the purposes of this description these may be regarded as one apartment.

I claim—

1. The combination in a range or stove of a horizontal flue adapted to carry off the products of combustion and extending from the fire chamber end of the stove and connecting with the fire chamber and provided with 45 a damper, and a branch vertical flue provided with a damper and connecting with the sifting (or ash) chamber as and for the purposes described.

2. The combination in a stove or range of a 50 horizontal flue extending from the fire chamber end of the stove and adapted to carry off the products of combustion and connected with the fire chamber, a branch vertical flue connecting with the sifting (or ash) chamber, 55 the apertures over or opposite the vertical flue and adapted to receive a collar or smoke pipe, and the dampers E and I.

JOHN BALLOU.
